UNITED STATES PATENT OFFICE.

ABRAHAM J. SHEKTER, OF HUNTINGTON, NEW YORK.

TONSILLOTOME.

Application filed December 2, 1922. Serial No. 604,475.

To all whom it may concern:

Be it known that I, ABRAHAM J. SHEKTER, a citizen of the United States, and a resident of Huntington, county of Nassau, State of New York, have invented certain new and useful Improvements in Tonsillotomes, of which the following is a specification.

My invention relates to tonsillotomes and has for its object to provide an instrument of this character which is reliable and efficient in operation with a minimum of effort on the part of the operator and which is capable of being controlled in a manner comfortable to the physician and with a minimum of manual effort. Other more specific objects will appear from the description hereinafter and the features of novelty will be pointed out in the appended claims.

Reference is to be had to the accompanying drawings which illustrate an example of the invention without defining its limits and in which Fig. 1 is a side elevation with parts in section; Fig. 2 is a plan view; Fig. 3 is a fragmentary section showing the parts in a different position; Fig. 4 is a cross-section on the line 4—4 of Fig. 3 and Fig. 5 is a detail view of a toothed pawl which forms part of the instrument.

The instrument comprises a main member 10 which is provided with a bore 11 and with a lengthwise extending slot 12, said member 10 being further formed with a smooth guide surface 13. At one end the main member 10 is constructed with a head 14 from which a tubular member 15 extends forwardly and in registry with a channel 16 extending through the head 14; at its free end the tubular member 15 terminates in a fenestra 17 which is interiorly grooved as indicated at 18 for the purpose to be set forth more fully hereinafter. A snare-wire 19 extends through the tubular member 15 and through the channel 16 of the head 14 and is connected with a slide 20 which is slidable lengthwise of the main member 10 upon the smooth guiding surface thereof; at its forward end the snare-wire 19 is arranged to form a loop 21 which is expanded to its fullest extent by the action of the groove 18 of the fenestra 17 when the slide 20 is moved in one direction and is gradually reduced in size by being withdrawn into the tubular member 15 when said slide 20 is moved in the opposite direction. In the preferred arrangement the snare-wire 19 is

attached to a plug 22 which, in turn, is removably mounted in the slide 20 and secured in connection therewith, for instance, by means of a set screw 23. A finger-piece 24 is carried by and projects downwardly from one side of the slide 20 and serves as a means whereby said slide 20 may be actuated rearwardly or away from the fenestra 17. A trigger 25 is pivotally connected at 25^a with the slide 20 and is located to the rear of the finger-piece 24 as shown in Figs. 1 and 3, the said trigger extending below the finger-piece as also illustrated in said figures; a pawl 26 forms part of or is secured to a spring member 27 which is attached at 28 to the slide 20; the pawl 26 is provided on its one face with teeth 29 so arranged as to mesh with the screw-threads of an adjusting screw 30 which is 75 rotatably mounted in the main member 10 and is held therein against lengthwise movement by means of a nut 31 screwed upon the screwthreaded neck 32 of said member 10 as shown in Fig. 1. Any suitable means such as a handle 33 may be provided for rotatably manipulating the screw 30 for the purpose to be more fully described hereinafter.

The pawl 26 projects through the forked end 25^b of the trigger 25 and is provided with a cam surface 26^a against which said trigger 25 exerts a pressure to force the pawl 26 into engagement with the screw 30 when said trigger is shifted from the position shown in Fig. 1 to the position shown in Fig. 3; the purpose of this arrangement will be more fully set forth hereinafter. For convenience of operation a thumb-piece 34 is provided upon the slide 20 to enable the same to be shifted forwardly upon the guide surface 13 to return the parts to their initial positions. The instrument further includes a hand-grip 35 in the form of a pistol grip and of a size and shape to comfortably fit the hand of the user of the instrument. In the preferred form this grip 35 is detachably mounted upon the main member 10 and is fixed in position thereon, for instance, by means of a set screw 36. In any case the grip 35 extends from the main member 10 in a direction at right angles to the plane of the fenestra 17 and is located in such a relation to the slide 20 and its finger-piece 24 and trigger 25 as to permit the latter to be comfortably and easily reached and manipulated by two

5 fingers of the same hand in which the grip 35 is grasped. As shown in Fig. 4 the finger-piece 24 is located somewhat to one side and out of registry with the trigger 25; with this arrangement the positions occupied by the finger located in the finger-piece 24 and the finger by which the trigger 25 is operated, are positively individualized so that interference of these fingers with 10 each other in the operation of the instrument and the possibility of unintentionally manipulating said slide 20 in an incorrect manner is reduced to a minimum. A trip 37 is located upon that portion of the grip 35 which 15 is fixed upon the member 10 and serves to automatically trip the trigger in a manner to be more fully described hereinafter.

In utilizing the instrument for its intended purpose the slide 20 is shifted forwardly 20 upon the surface 13 as far as it will go, this being possible because the parts occupy the position shown in Fig. 1. In the described adjustment of the slide 20 the loop 21 of the snare-wire 19 lies within the groove 18 of the fenestra 17 and is entirely out of the way. The fenestra is then placed over the tonsil in the customary manner after which a pull is exerted upon the finger-piece 24 to move the slide 20 in a direction away from 25 the fenestra and to gradually withdraw the snare-wire 19 into the tubular member 15 whereby the loop 21 is gradually reduced in size; this is continued until the loop 21 has been so adjusted as to strangle the tonsil. 30 As soon as the loop has been adjusted to bring about this result the trigger 25 is pivotally pressed rearwardly by another finger of the same hand to the position shown in Fig. 3 and by a pressure upon the surface 25^a, forces the teeth 29 of the pawl 26 into engagement with the screw-threads of the screw 30 and thereby locks the slide 20 upon the member 10 so as to maintain the snare loop in its adjusted position. At such time 40 as it is desirable to excise or complete the separation of the tonsil the handle 33 is rotated and thus brings about a rotation of the adjusting screw 30. Because of the engagement of the pawl 26 with said screw 30 this operation causes the slide 20 to move 45 rearwardly upon the surface 13 to a further extent which causes a further reduction in the size of the snare-loop 21 and finally causes the snare-wire to completely excise 50 the tonsil. This adjustment of the parts through the medium of the screw 30 is continued until the one member of the fork 25^b of the trigger 25 engages the trip 37 whereupon said trigger is shifted back to the position shown in Fig. 1 in which the pawl 26 55 automatically releases itself from the screw 30 because of the inherent resiliency of the member 27. The slide 20 may thereupon be returned to its forward position in a comfortable manner by exerting a pressure upon 60 65

the thumb-piece 34 whereby the snare-loop 21 is again extended into the groove 18 of the fenestra 17. During these operations the grip 35 is securely held in the one hand of the physician and serves to place said instrument under complete and easy control while at the same time two of the fingers of the hand are left free to manipulate the finger-piece 34 and the trigger 25 with a minimum of effort upon the part of the physician. Because of the fact that the grip 35 extends in a direction at right angles to the plane of the fenestra 17 all parts of the instrument, when the latter is in use, occupy such positions as to enable the physician to utilize said instrument in a most efficient manner with a minimum of attention to correctly position the same; the physician is thus left free to give his entire attention to the tonsils which are to be excised. Because of the absence of serrations or teeth upon the guide surface 13 it is possible to adjust the slide to the minutest degree desirable, such adjustment in no sense depending upon the engagement of serrations or teeth with some element of the slide; in addition, the absence of such serrations on the guide surface brings about a more even and uniform sliding movement of the slide and reduces vibration in the instrument and thereby increases the control thereof by the physician. The detachability of the grip 35 is desirable in that it enables the instrument to be packed into a relatively small compass. The arrangement of the pawl 26 upon a resilient member 27 enables this unit to be removed from the instrument when this is desirable for cleaning or other purposes; at the same time the arrangement shown and described makes the operation of the pawl a most positive one and reduces the effort necessary to actuate the same to a minimum. To release the pawl it is simply necessary to give the trigger 25 a slight movement toward the fenestra 17, the movement itself being completed by the camming action of the surface 26^a upon said trigger 25 under the influence of the resilient member 27.

Various changes in the specific form shown and described may be made within the scope of the claims without departing from the spirit of my invention.

I claim:—

1. A tonsillotome comprising a carrier 120 terminating at one end in a fenestra and having a smooth guide surface, a snare-wire movable relatively to the fenestra, a slide connected with said wire and slidable on said guide surface, a finger-piece connected with said slide and extending downwardly therefrom for slidably actuating the same to operate said snare-wire, a trigger pivotally connected with said slide and located rearwardly of said finger-piece in 125 130

contiguous relation thereto, means operated by a rearward movement of said trigger for locking said slide in an adjusted position, mechanism for shifting said slide from said 5 adjusted position when said means is in locked position and a grip connected with said carrier and extending therefrom in a direction at right angles to the plane of said fenestra.

10 2. A tonsillotome comprising a carrier terminating at one end in a fenestra and having a smooth guide surface, a snare-wire movable relatively to the fenestra, a slide connected with said wire and slidable on 15 said guide surface, a finger-piece connected with said slide and extending downwardly therefrom for slidably actuating the same to operate said snare-wire, a trigger pivotally connected with said slide and located 20 rearwardly of said finger-piece in contiguous relation thereto, a rotatable adjusting screw, a resilient pawl controlled by said trigger and arranged to be adjusted by a rearward movement thereof into engagement 25 with said adjusting screw, means for rotating said screw to shift said slide from said adjusted position and a grip connected with said carrier and extending therefrom in a direction at right angles to the plane of 30 said fenestra.

3. A tonsillotome comprising a main member having a smooth guide surface, a tubular member projecting forwardly from said main member and terminating in a fenestra, a snare-wire in said tubular member and adjustable relatively to said fenestra in the form of a gradually decreasing loop, a slide connected with said snare-wire and slidable on said guide surface, a finger-piece connected with the slide for slidably actuating the same to operate said snare-wire, an adjusting screw rotatably mounted in said main member, a toothed pawl mounted on said slide, a trigger pivotally connected with said slide and located rearwardly of 40 said finger-piece for throwing said pawl into engagement with said screw whereby said slide and snare wire are located in an adjusted position, a device for rotating said screw to slidably shift said slide from its 45 adjusted position, a thumb-piece on said slide for moving it forwardly on said guide surface and a hand grip detachably connected with said main member and extending therefrom in a direction at right angles 50 to the plane of said fenestra.

In testimony whereof I have hereunto set my hand.

ABRAHAM J. SHEKTER.
